Primary Examiner — Elizabeth A. Albert(74) *Attorney, Agent, or Firm* — Eugenio J. Torres-Oyola;
Victor M. Rodriguez-Reyes; Rafael Rodriguez-Muriel(57) **CLAIM**

The ornamental design for a children's drawing board, as shown and described.

DESCRIPTION

FIG. 1 is a front, top perspective view of a children's drawing board showing my new design;

FIG. 2 is a front, bottom perspective view thereof;

FIG. 3 is a back, top perspective view thereof;

FIG. 4 is a front view thereof;

FIG. 5 is a back view thereof;

FIG. 6 is a left side view thereof;

FIG. 7 is a right side view thereof;

FIG. 8 is a top view thereof; and,

FIG. 9 is a bottom view thereof.

The broken lines shown in the drawings are for the purpose of illustrating portions of the children's drawing board that form no part of the claimed design.

1 Claim, 9 Drawing Sheets(56)
